UNITED STATES PATENT OFFICE.

CARLO TOMMASI, JOHN SANDHOLM, HEINRICH DANNEEL, AND AUGUSTO BUSCH, OF BASEL, SWITZERLAND, ASSIGNEES TO ELEKTRIZITATSWERK LONZA, OF GAMPAL, CANTON OF VALAIS, SWITZERLAND, A CORPORATION OF SWITZERLAND.

BURNER FOR BURNING METALDEHYDE.

Application filed July 19, 1921. Serial No. 485,950.

(GRANTED UNDER THE PROVISIONS OF THE ACT OF MARCH 3, 1921, 41 STAT. L., 1313.)

To all whom it may concern:

Be it known that we, CARLO TOMMASI, a subject of the King of Italy, JOHN SANDHOLM, a citizen of the Republic of Finland, 5 HEINRICH DANNEEL, a citizen of the German Republic, and AUGUSTO BUSCH, a subject of the King of Italy, all residents of Basel, Switzerland, have invented a new and useful Burner for Burning Metalde- 10 hyde (for which applications have been filed in Switzerland on December 4, 1919, and April 24, 1920), of which the following is a full, clear, and exact description.

This invention relates to a burner which 15 uses as fuel a body made of metaldehyde, wherein a part of the fuel body, is surrounded by a protecting sheath and the fuel body and the upper edge of the protecting sheath are so adjustable relatively to each other 20 that the size of the burning surface of the fuel body can be regulated.

The burner may have a device which tends 25 to advance automatically the fuel body correspondingly with its consumption, and is combined with a retainer adjustable with respect to the upper edge of the protecting sheath, this retainer limiting the extent to which the fuel body protrudes from the sheath.

30 Furthermore, the arrangement may be such that on the one hand the burner has a device which tends to advance automatically the fuel body correspondingly with its consumption and on the other hand the protecting sheath is formed of two-coaxial relatively movable parts one of which has a retainer fixed to it to limit the extent to which the fuel body protrudes from the sheath, one of the said parts being further 35 so movable by the action of the weight of the object to be heated by the burner flame that the fuel body is more or less uncovered according to the weight of the said object.

40 Advantageously the protecting sheath may be formed at least near its upper edge of a material that is a bad conductor of heat.

45 For the purpose of obtaining first a large, intense flame and then a smaller, as is desirable, for example, in the preparation of soup, the above specified protecting sheath may be surrounded by a carrier in the form

of a cup on which can be placed a supplementary quantity of the metaldehyde in the form of tablets or the like. This carrier is 55 perforated to permit passage of air. The retainer which limits the extent to which the fuel protrudes from the sheath, may be carried by this cup-shaped carrier, and the latter may be raised or lowered, by a screwing 60 operation, in relation to the protecting sheath, or the cup-shaped carrier may be connected suitably with the sheath and the retainer may be formed of at least one metal wire extending through inclined slots in a 65 part of the said carrier.

In order that while the large flame is burning the metal parts of the protecting sheath may not become hot enough to vaporize the fuel within it, the cup-shaped 70 carrier and the sheath may be separated by material that is a bad conductor of heat, or parts of the apparatus, such as the lower part of the said carrier or the sheath itself, or both, may be made of a material which 75 is a bad conductor of heat.

Three examples of the construction according to the invention are shown in the accompanying drawing.

Figs. 1, 2 and 3 shew a first construction 80 in vertical section, side elevation and plan respectively.

Fig. 4 shews a second construction partly in vertical section and partly in side elevation.

Fig. 5 shows a third construction in vertical section.

Referring to Figs. 1-3, A is the fuel body of metaldehyde, B is the protecting sheath which surrounds a part of it and may be formed wholly or only as to its upper part of heat insulating material in order to hinder conduction of the heat of the flame to the lower parts of the burner. The spring C, bearing upon the foot J with which the sheath B is connected, presses through a plate D the fuel body A against a retainer E, consisting of a wire cross, which limits the extent to which the body A protrudes from the sheath B. In this case the retainer is fixed 90 to the sheath and its adjustability with respect of the upper edge of the sheath is obtained by making the latter in two parts, one of which can be moved coaxially on the 95 100

other. Thus mounted on the sheath B is a ring F in which are two oblique slots G engaging pins H fixed to the sheath, so that by partially rotating the ring the latter can be adjusted vertically on the sheath; thus the height of the portion of the fuel body, which always bears against the retainer E, protruding from the sheath, of which the ring F forms a part, can be varied. The foot J is connected with the sheath by a double bayonet joint K, L so that these parts can be separated for the purpose of introducing the fuel body into the sheath.

In Fig. 4 the fuel body A is again partially surrounded by a protecting sheath and is pressed against the retainer E by the spring C acting through the plate D. The sheath is formed of two concentric parts B', F' of which B' has the retainer E fixed to it and is connected with the foot J in such a manner that it can be lifted from the foot. The part F' can slide vertically on the part B' and is connected with the curling tongs carrier N. When nothing rests on the carrier N, the part F' has a position in which it extends above the upper edge of part B' and partially covers the protruding portion of the fuel body. When, however, the curling tongs M are laid upon the carrier, the latter together with the outer part F' of the sheath is pushed downwards so that an increased surface of the fuel body is freely exposed and the flame becomes correspondingly larger. When the tongs M are again removed from the carrier N, the latter and the parts F' are again raised under action of springs P and the flame diminishes. In Fig. 4 the part F' is shown in its lowest position.

The possibilities of construction are not exhausted by this example. The outer sheath F' for instance, may be immovable and the inner sheath together with the fuel body, spring C and retainer E may be connected with the carrier N, such as by a lever device, so that when the object to be heated is put in place the fuel body is raised and its exposed surface increased, while when the object is removed the weight of the fuel body causes it to return into the outer sheath and burn with a small flame. In this case also there would be two co-axial sheaths, the relative movement of which would be determined by the placing in position of the object to be heated and the size of the flame thus regulated.

In Fig. 5 the sheath B, closed at its lower end contains the solid fuel A and a spring C in compression between the bottom of the sheath and a plate D on which the fuel is supported.

The sheath is carried by a foot J on which is mounted, by means of a screw thread S, a perforated carrier T shaped like a cup and having the retaining wire E' extending

through two perforations in what may be called the neck t of the carrier; the fuel is pressed against this wire by spring c. When the carrier is turned on its axis simultaneously with the wire E' it is screwed up or down on the foot J and the extent of the surface of the fuel which can burn is thus adjusted.

The neck t of the carrier is separated from the sheath B, almost throughout its height, by a space U and is perforated to ensure an ascending current of air in this space and thus to avoid or counteract transmission of heat to the sheath B through the screw connection S. A layer of asbestos, of a mixture of Portland cement with the asbestos fibres, or other bad conductor of heat may be arranged between the fuel A and the sheath B. The neck t or the sheath B or both may also be made of glass, porcelain, a mixture of Portland cement with asbestos fibres, or any other suitable material which is a bad conductor of heat.

The wire E' may be adjusted relatively to the upper edge of the sheath B in any other manner than that shown; for instance the screw thread S may be omitted and the wire may extend through inclined slots in the sheath B.

To start the burner, the necessary tablets of metaldehyde, judged from experience to be necessary for bringing to the boil the substance to be heated or cooked, are thrown on to the carrier T, and ignited. When these tablets have been consumed the surface of the body of fuel A protruding from the sheath will continue to burn, furnishing a smaller flame. Instead of the wire E' there may be used one or more stirrups of wire fixed to the sheath B or to the neck t or another part of the carrier T; or there may be several wires like E' arranged parallel or crossing each other; or a metal gauze may be used.

What we claim is:

1. A burner for fuel bodies of metaldehyde wherein a part of the fuel body is surrounded by a protecting sheath and the fuel body and the upper edge of the sheath are so adjustable in relation to each other, that the size of the burning surface of the fuel body can be regulated.

2. A burner for fuel bodies of metaldehyde, having a protecting sheath surrounding a part of the fuel body, a device which tends to push forward automatically the fuel body correspondingly with its consumption and a retainer, which limits the extent to which the fuel body protrudes from the sheath, the said retainer and the upper edge of the protecting sheath being so adjustable in relation to each other, that the size of the burning surface of the fuel body can be regulated.

3. A burner for fuel bodies of metalde-

- hyde, having a protecting sheath surrounding a part of the fuel body, a device which tends to push forward automatically the fuel body correspondingly with its consumption and a retainer, which limits the extent to which the fuel body protrudes from the sheath, the said retainer and the upper edge of the protecting sheath being so adjustable in relation to each other, that the size of the burning surface of the fuel body can be regulated and the said protecting sheath being formed, at least near its upper edge, of a material which is a bad conductor of heat.
15. 4. A burner for fuel bodies of metaldehyde wherein a part of the fuel body is surrounded by a protecting sheath and the fuel body and the upper edge of the sheath are so adjustable in relation to each other, that the size of the burning surface of the fuel body can be regulated, the protecting sheath being formed, at least near its upper edge, of a material which is a bad conductor of heat.
20. 5. A burner for fuel bodies of metaldehyde having a protecting sheath surrounding a part of the fuel body, a cup-shaped carrier perforated for passage of air, arranged around the protecting sheath and adapted to receive a supplementary supply of metaldehyde in the form of tablets or the like, a device which tends to push forward automatically the fuel body correspondingly with its consumption and a retainer for the said fuel body, mounted on the said cup-shaped carrier and being vertically adjustable relatively to the upper edge of the protecting sheath.
25. 6. A burner for bodies of metaldehyde having a protecting sheath surrounding a part of the fuel body, a cup-shaped carrier perforated for passage of air, arranged around the protecting sheath and adapted to receive a supplementary supply of metaldehyde in the form of tablets or the like, a device which tends to push forward automatically the fuel body correspondingly with its consumption and a retainer for the said fuel body, mounted on the said cup-shaped carrier and being vertically adjustable relatively to the upper edge of the protecting sheath.
30. 7. A burner for bodies of metaldehyde having a protecting sheath surrounding a part of the fuel body, a cup-shaped carrier perforated for passage of air, arranged around the protecting sheath and adapted to receive a supplementary supply of metaldehyde in the form of tablets or the like, a device which tends to push forward automatically the fuel body correspondingly with its consumption and a retainer for the said fuel body, mounted on the said cup-shaped carrier and being vertically adjustable relatively to the upper edge of the protecting sheath.
35. 8. A burner for bodies of metaldehyde having a protecting sheath surrounding a part of a fuel body and constructed of a material which is a bad conductor of heat, a cup-shaped carrier perforated for passage of air, arranged around the protecting sheath and adapted to receive a supplementary supply of metaldehyde in the form of tablets or the like, a device which tends to push forward automatically the fuel body correspondingly with its consumption, and a retainer for the fuel body, mounted on the said cup-shaped carrier, and being vertically adjustable relatively to the upper edge of the protecting sheath.
40. 9. A burner for bodies of metaldehyde having a protecting sheath surrounding a part of a fuel body and constructed of a material which is a bad conductor of heat, a cup-shaped carrier, perforated for the passage of air, arranged around the protecting sheath and adapted to receive a supplementary supply of metaldehyde in the form of tablets or the like and having its lower part formed of a material which is a bad conductor of heat, a device which tends to push forward automatically the fuel body correspondingly with its consumption, and a retainer for the fuel body, mounted on the said cup-shaped carrier and being vertically adjustable relatively to the upper edge of the protecting sheath.
